UNITED STATES PATENT OFFICE.

JOHN T. S. BROWN, JR., OF PROSPECT, KENTUCKY.

PUMP.

1,156,882.

Specification of Letters Patent.

Patented Oct. 19, 1915.

Application filed November 18, 1914. Serial No. 872,700.

To all whom it may concern:

Be it known that I, JOHN T. S. BROWN, Jr., a citizen of the United States, residing at Prospect, county of Jefferson, and State of Kentucky, have invented a certain new and useful Improvement in Pumps, of which the following is a specification.

This invention relates to improvements in pumps with particular reference to that class known as "tube" or "deep well" pumps.

An object is the provision of a pump which will deliver a constant stream of water, thereby conserving the energy delivered to the pump.

A further object is to produce a pump of the class described which will be economical in construction, efficient in operation and durable in service.

With the foregoing and other objects in view, the invention consists of the novel arrangement and construction of parts, illustrated in the accompanying drawing, which forms a part of this specification, wherein is set forth an embodiment of the invention, but it is to be understood that such changes and modifications may be resorted to as come within scope of the claims appended hereunto.

Referring to the drawing wherein like reference characters designate similar parts in the several views: Figure 1, is a central vertical section, with portions broken away and parts in elevation, showing the plunger near the completion of its downward stroke; Fig. 2, a view similar to Fig. 1, showing the plunger near the completion of its upward travel; Fig. 3, a transverse section on line X—X of Fig. 2; Fig. 4, a perspective of the guide ring; Fig. 5, a plan of the side valve spring.

Referring to the drawing, the reference characters —A—, —B—, and —C— designate respectively three portions or sections of the pump, *i. e.* a working barrel, a valve chamber, and a discharge tube which are secured together at their points of connection in any of the usual ways known to the art. The working barrel, is preferably constructed of seamless brass tubing, a foot valve —2— being removably secured in the lower end thereof by suitable means, that illustrated herewith being a lead packer —3— such as is well known in the art. The valve illustrated is of a type well known in the art as a ball valve and comprises a cage —4— and a ball —5— adapted to close an

inlet —6—. Within the working barrel is a hollow piston, or plunger, —7— provided with a plurality of piston rings —8—, which is open at the bottom and closed at the top by an arch —9—. In the interior of the piston near the upper end thereof is a septum —10— on the upper face of which is a ball valve —11— which prevents a downward flow of fluid through an opening —12—. The rise of the valve is limited by lugs —13— which extend inward from the arched inclosure 9. Connected to the upper end of the plunger and in connection with the interior thereof, is a hollow piston rod —14—, provided on its upper end with suitable means for the attachment thereto of a pump rod —15— which extends upward to a point of connection with a suitable actuating force. In the side wall of the piston rod, near the upper end thereof are a plurality of outlets —16—, the total area of which is substantially equal to that of the opening through the piston rod. These outlets are arranged in staggered relationship so as not to weaken the rod. The pump rod is provided with side extensions, or wings —17— adapted to contact with the sides of the discharge tube to prevent side lash of the pump rod during the down stroke.

A plurality of inlet openings, or ports, —18— are disposed about the walls of the valve chamber. The flow of fluid therethrough being controlled by valves —19— each of which comprises a body portion —20— the face of which is contoured to conform to the curvature of the walls of the chamber and covered with a layer of suitable packing material —21— such as leather secured thereto by metallic plates —22—. The valve is carried on the end of a flexible member, or strap —23— which is secured on an abutment, or block, —24—. The valve is connected with the strap by means of pins —25— which extend through elongated openings —26— in the strap. This method of connection by allowing restricted vertical movement of the valve while preventing any lateral movement thereof, facilitates the proper seating of the valve. The top of the block 24 is curved transversely, relative to the strap 23 and the strap is secured thereon by means of bolts —27, and 28—, which extend through the walls of the chamber, through the block 24, emerging therefrom on each side of the crown of the curved top, and through perforations —29— in the

strap. A bolt —30— which extends through the walls of the chamber and through a perforation —31— in the strap provides means of limiting the inward movement of the 5 valve that it may not contact with the piston rod. The tension of the strap may be adjusted by means of the bolts 27 and 28. Tightening up the bolt 27, will draw the strap down about the top of the block 24 and 10 increase the pressure exerted on the valve. It is to be understood that securing means will be used in connection with the bolts 27, 28, and 30, such as lock nuts, castellated nuts or other suitable means. Immediately above 15 the valves 19, an annular ledge —32— extends inward from the wall of the chamber and forms a seat for a valve. The ledge is spaced from the piston rod leaving a passage —38—. A sleeve —33— adapted to slide on 20 the piston rod, has an annular enlargement —34— which rests on the upper face of the seat 32, and forms a cutoff valve which closes the passage 38 during the downward stroke of the piston. A ring —35— disposed about 25 the piston rod, and spaced from the sides of the chamber by lateral arms, or lugs, —36—, is secured in position by screws —37— and serves to limit the lift of the valve 34 and acts as a guide for the piston rod.

30 The operation of my improved pump is as follows: When the piston is on the up stroke as illustrated in Fig. 2, the water is drawn in through the foot valve filling the lower portion of the working chamber, and such of the water as is held in the chamber 35 above the piston is forced up, its pressure serving to close the side inlet valves 19 and to raise the valve 34 on the piston rod, as shown, which operation opens up a free 40 communication between the working chamber and the discharge tube through the passage way —38—, it being obvious that during such operation the ball valve 11 will be forced back by the pressure of the water 45 to close the port 12 in the upper end of the plunger 7. When however, the piston is forced down as indicated in Fig. 1, the pressure will close the foot valve and force the water beneath the piston up there- 50 through lifting the ball valve 11 and passing through the openings 16, in the side of the piston rod, into the discharge tube C. It will be observed that during this operation the water in the discharge tube will be pre- 55 vented from entering the upper portion of the working chamber by closing of the slide valve 34 which is held closed by the weight of the water pressing down thereon. At the same time the upper part of the chamber 60 is refilled through the side valves 19. It will be seen that a continued flow of water is maintained through the discharge tube

during the operation of the pump. It is to be understood that the side inlet valves may be placed in an integral extension of the 65 working chamber, instead of a separate section as illustrated, without departing from the spirit of the invention. It will be observed that the arrangement illustrated permits of a ready removal of parts 70 for repairs and adjustments.

It is thought that the many advantages of my invention may be readily understood from the foregoing description, and that anyone skilled in the art may make and use 75 the same, and

I claim:

1. In a pump, a valve comprising a supporting block having a convex top, a resilient member extended from said block 80 and secured thereon by adjustable attachment means positioned respectively on each side of the apex thereof, said resilient member having elongated openings near the outer ends thereof, and a valve connected 85 to said member by means of bolts passing through said openings.

2. In a pump, a supporting block with a convex top secured on the inner wall of the pump cylinder, a resilient member ex- 90 tended from said block and secured thereon by adjustable attachment means positioned respectively on each side of the apex thereof, said resilient member having elongated openings near the outer end thereof, a valve 95 connected to said member by means of bolts passed through said openings, and means extended from the walls of the cylinder to limit the travel of the valve.

3. In a pump the combination of a valve 100 chamber having a port, a convex seat adjacent said port, a strap adjustably mounted on said convex seat and a valve carried by said strap and adapted to open and close the port in the valve chamber.

4. In a pump, the combination of a valve chamber having a port, a convex seat adjacent said port, a flexible strap adjustably mounted on said convex seat and a valve carried by said strap and adapted to open 110 and close the port in the valve chamber.

5. In a pump the combination of a valve chamber having a port, a convex seat adjacent said port, a flexible strap mounted on 115 said seat and adjustably secured thereon by fastening devices located at opposite sides of the crown of the convex seat and a valve carried by said strap and adapted to open and close the port in the valve chamber.
